CLAIM

The ornamental design for the food tray with waste collection feature, as shown and described.

DESCRIPTION

FIG. 1 is a perspective view of a food tray with waste collection feature showing our new design;

FIG. 2 is a rear elevation thereof;

FIG. 3 is a front elevation thereof;

FIG. 4 is a right side elevation thereof;

FIG. 5 is a left side elevation thereof;

FIG. 6 is a top plan view thereof;

FIG. 7 is a bottom plan view thereof;

FIG. 8 is another bottom plan view thereof showing a planar and modified embodiment;

FIG. 9 is a top plan view of the design shown in FIGS. 1 through 8 in an open position;

FIG. 10 is a bottom plan view thereof; and,

FIG. 11 is a rear elevation thereof.
